UNITED STATES PATENT OFFICE.

JOSEPH J. HARRELL, OF CHICAGO, ILLINOIS, ASSIGNOR OF THREE-FOURTHS
TO CHARLES H. ABBOTT AND WILLIAM W. HESSEY, OF DENVER, COLORADO.

WOOD-PULP-MAKING MACHINE.

SPECIFICATION forming part of Letters Patent No. 592,090, dated October 19, 1897.

Application filed December 14, 1896. Serial No. 615,674. (No model.)

To all whom it may concern:

Be it known that I, JOSEPH J. HARRELL, a citizen of the United States, residing at Chicago, in the county of Cook and State of Illinois, have invented certain new and useful Improvements in Wood-Pulp-Making Machines; and I do declare the following to be a full, clear, and exact description of the invention, such as will enable others skilled in the art to which it appertains to make and use the same, reference being had to the accompanying drawings, and to the letters of reference marked thereon, which form a part of this specification.

The invention relates to that class of wood-pulp mills in which the reduction is accomplished by the impact of beaters co-operating with fixed portions of the machine, and is an improvement in certain particulars upon the machine forming the subject-matter of my application for Letters Patent filed July 9, 1896, Serial No. 598,544.

The objects of the invention are to provide for the reduction of the material from the block form to the chip form in connection with the pulverizing mechanism; to better provide for the agitation of the pulp within the reducing-chamber, and to prevent the clogging of the discharging-screen.

With these objects in view it consists in so constructing and arranging the machine that it is provided with a cutting or chipping device at the mouth of a hopper adapted to receive the material in block form, and which feeds the reducing-mill; in so forming the enclosing case that it is provided with a large chamber above the beaters into which the pulp is thrown from the beaters by centrifugal action, the wall of this chamber against which the pulp is so discharged being so curved that the material is thrown forwardly, so that it may descend by the action of gravity among the beater-arms, and in so forming the ribs or bars of the discharging-screen that the agitation of the pulp will tend to dislodge from the screen-aperture any large particles which may gather therein.

In the drawings, Figure 1 is a front elevation of the machine. Fig. 2 is a transverse

vertical section thereof upon the line 2 2 of 50 Fig. 1. Fig. 3 is a longitudinal vertical section upon the line 3 3 of Fig. 2.

The shell or casing of the machine A is oblong rectangular in its general contour, and is horizontally divided into two sections, the lower one *a* forming the bottom of the casing, and being apertured to receive the discharging-screen, which is curved in form, the arc of curvature having the axis of the beater-shaft as its center. This shaft C is journaled longitudinally within the casing A, and upon it are mounted a plurality of disks D, having radiating arms *d*, as shown, eight in number. These disks are spaced apart by means of rings F, which, together with the disks, are keyed upon the shaft. The disks D are so set upon the shaft that the beater-blades *d* are arranged in spiral form, the spiral running from the middle of the machine to its sides, in one direction taking the form of a right screw-thread and in the other a left screw-thread, so that as the beaters revolve they tend to move the pulp continuously toward the sides of the machine. A plurality of blades E are fixed in one of the side walls 75 of the casing A and project inwardly, intermeshing with the beater-blades and terminating beyond their bases, the inner ends of these blades being thickened, as indicated at *e*, so as to bear against the surface of adjacent disks D. The blades E are held in this machine in the same manner as in the earlier machine above referred to, being set within a recess formed between the attaching-flanges of the upper and lower sections of the casing, 80 and being locked in place by means of a rib *a'*, engaging transverse notches in the blades, the blades being spaced apart by the introduction of suitable blocks *e'*.

The screen consists of the two slotted plates G H, the former being the inner one, being in fixed relation with the bottom *a* of the casing, and the outer one being adapted to slide upon its companion, and being held in frictional contact therewith by means of the curved bars J, pivoted at *j* to one side of the bottom *a* of the casing and secured by means of bolts *j'* to the other side thereof, the

outer ends of the bars J being united by means of the plates J'. The inner faces of the bars of the screen G are beveled, so as to present an inclined face to the pulp as it is carried forward by the action of the beaters, so that the inner face of the screen presents the appearance of a series of grooves having an abrupt and an inclined wall, thereby forming an abutment over which the pulp is precipitated, and preventing slivers of wood from being driven into the interstices of the screen, and allowing any particles which may seek lodgement therein to be quickly washed out by the agitation of the material.

15 The adjustment of the screen, as in the case of my earlier machine, is accomplished by means of a crank-handle K, fixed upon a rock-shaft k, journaled within the bars J and having fingers k² engaging suitable sockets in the bands k³, secured to the outer plate H of the screen.

20 The casing A extends upwardly above the beaters, so as to form a suitable chamber into which the pulp is discharged from the beaters by centrifugal action. That wall of the casing along which the pulp is thus discharged is curved inwardly at its upper end, as indicated at a', so that the pulp is thrown forwardly and descends upon the beaters by the action of gravity. By this means I am able to return the pulp to the inner portions of the beaters, the centrifugal action tending at all times to carry it to their outer ends. A casing B, of less length than the casing A, is superimposed upon the latter and is secured thereto by the hinge B' at one side and by bolts B² at the other side. Within the casing B the top of the casing A is apertured to receive the material, and an apron L extends from one side of this aperture obliquely downwardly, so as to receive the impact of the pulp, then upwardly from the beaters, and terminates a sufficient distance from the side wall of the casing A to permit the entry of fresh material. The top of the casing B is open, serving as the mouth of a hopper, which consists in part of the walls of the casing and in part of a swinging plate b, pivoted within the casing and supported by a screw-threaded rod b', projecting through the casing - wall and being provided with a hand-wheel. Between the mouth of the hopper thus formed and the apron L is journaled a horizontal cylinder M, carrying the cutting-blades m m.

45 The wood to be operated upon is introduced into the hopper in the form of blocks X, which fall upon the face of the cylinder M, so that the cutting-blades gradually reduce them by chipping, the chips being carried downwardly and delivered into the reducing - chamber. A horizontal pipe l extends longitudinally through the casing immediately below the cylinder M and is provided throughout its length with small discharge - apertures, by

65 which means a suitable quantity of water may

be delivered to the machine with the chips. The cylinder M is driven from the shaft C by means of a belt O upon suitable pulleys upon this shaft and the shaft of the cylinder. A belt-tightener in the form of an idle-pulley P coöperates with the belt, being suitably journaled in the arms p p, projecting from a sleeve Q, mounted upon a shaft q, secured in brackets attached to one of the sides of the casing A. The sleeve Q is controlled by a handle-bar R and is locked in an advanced position by means of a ratchet-wheel r and a pawl S. By this means a loose belt may be employed, so that when desired the cutting-cylinder M may be stopped without interfering with the action of the beaters, so that if the chips are fed to the pulverizer too rapidly the clogging of the machine may be prevented.

The upper edges of the blades E are inclined, as shown in Fig. 2, downwardly from the wall of the casing, so that by impact of the chips upon these blades they are thrown toward the center of the beater-cylinder and prevented while in this larger form from being thrown directly against the screen. After the material has become finely subdivided, this incline form of the upper edge of the blades ceases in great measure to divert them to the center, so that the effect of thus forming the plate is measurably to assort the coarser from the finer material, leaving the latter free to seek by the centrifugal action to escape through the screen. Near their inner ends the top edges of the blades are given an upward inclination, so as to prevent the material from being carried too far to the center and into the space between the disks D.

The plate b, forming one of the walls of the hopper, is mounted upon a pivot, as shown, so that the capacity of the hopper may be varied to adapt the machine to the character of material being operated upon. Should the material be hard and require a longer time for reduction, it is obvious that the feed should be slower, and this is secured by advancing the plate b so as to contract the throat of the hopper and thereby reduce the number of blocks in contact with the cutting-blades, and consequently the quantity of chips delivered to the pulverizing-chamber. When wood is used, which is more readily reduced, the plate b may be moved backwardly, permitting a greater number of blocks to come into contact with the blades, and thus increasing the quantity of chips produced.

I claim—

1. In a wood-pulp mill the combination with a plurality of beaters mounted upon a horizontal shaft, a case for inclosing such beaters, and having an enlarged chamber above the beaters to receive the pulp thrown therefrom by centrifugal action, the roof of such chamber being curved to direct the pulp forward in the direction of rotation of the beaters. 130

2. In a wood-pulp mill the combination with a plurality of rotatable beaters, and a casing for inclosing such beaters of a slotted discharge-screen, the bars of which have their inner faces beveled outwardly in the direction oppositely to the direction of rotation of the beaters.

In testimony whereof I affix my signature in presence of two witnesses.

JOSEPH J. HARRELL.
